EX

CLOCK CASE.

No. 15,673.

Patented Dec. 30, 1884.

UNITED STATES PATENT OFFICE.

CARL VOTTI AND GEORGE C. NEWMAN, OF PHILADELPHIA, PA.

DESIGN FOR A CLOCK-CASE.

SPECIFICATION forming part of Design No. 15,673, dated December 30, 1884.

Application filed October 18, 1884. Term of patent 7 years.

To all whom it may concern:

Be it known that we, CARL VOTTI and GEORGE C. NEWMAN, both citizens of the United States, residing in the city and county of Philadelphia, State of Pennsylvania, have invented and produced a new and original Design for a Clock-Case, of which the following is a specification, reference being had to the accompanying photographic illustration forming part thereof.

The upper part of the body of the case has at each side a figured column, *a*, at bottom a figured cross-bar, *b*, and at top a figured cross-bar, *c*. Rising from the bar *c* is a cornice, *d*, formed of columns *e* and a capital, *f*. The base *g* and cap *h* of each column *a* are ornamented, and on the caps *h* are triangular ornaments *k*, which latter are surmounted by rosettes *m*, the ornaments *k* thus flanking the cornice *d*. The dial-door *n* has a figured face, *n'*, and the portion of the face of the case around said door and between the columns *a* and bars *b* *c* is mottled, as at *p*. The lower part, *r*, of the case or pendulum portion thereof has a figured face and a door, *s*, with a figured face. At the upper and lower corners of the part *r* are scrolls *t* *u*, the scrolls *t* rising from the sides of said part *r* and joining the bases *g* of the columns *a*. The scrolls *u* are joined centrally at the bottom of the part *r* of the case by a shell, *v*.

We claim—

1. A design for a clock-case, the top of which has a cross-bar, *c*, side caps, *h*, a cornice, *d* *e* *f*, on said cross-bar, ornaments *k* on the caps *h*, and rosettes *m*, surmounting said ornaments, as shown and described.
2. A design for a clock-case, the body of which has side columns, *a*, upper and lower cross-bars *c* *b*, caps *h* on the top of said columns, and bases *g* at the bottom of the same, and a figured dial-door, *n*, as shown and described.
3. A design for a clock-case, the bottom portion, *r*, of which has scrolls *t* at the upper corners, scrolls *u* at the lower corners, and a shell, *v*, covering the scrolls *u*, as shown and described.
4. A design for a clock-case having a body with side columns, *a*, upper and lower cross-bars, *c* *b*, caps *h*, bases *g*, and a dial-door, *n*, a top part with a cornice, *d* *e* *f*, rising from the cross-bar *c*, and ornaments *k*, with rosettes *m* on the caps *h*, and a bottom part, *r*, with a door, *s*, top corner scrolls, *t*, bottom corner scrolls, *u*, and a shell, *v*, joining the bottom scrolls, as shown and described.
